UNITED STATES PATENT OFFICE.

WILLIAM EDENBORN, OF CHICAGO, ILLINOIS.

DESIGN FOR A FENCING-PATTERN.

SPECIFICATION forming part of Design No. 25,380, dated April 14, 1896.

Application filed January 27, 1896. Serial No. 577,067. Term of patent 14 years.

To all whom it may concern:

Be it known that I, WILLIAM EDENBORN, a citizen of the United States, and a resident of Chicago, Cook county, Illinois, have invented and produced a new and original Design for Fencing, of which the following is a specification, reference being had to the accompanying drawing, showing a part thereof.

The drawing is an elevation, showing a section of fencing made in accordance with my design.

The leading feature of my design is a number of longitudinal parallel single strands connected by short transverse independent single strands, each of these latter strands being wound at its ends about two adjacent longitudinal strands and forming single coils having, respectively, an upwardly and downwardly projecting point.

In the drawing, 1 represents the longitudinal parallel single strands. These strands are arranged closer together at the bottom than at the top of the fencing.

2 represents the short transverse independent single strands, the ends of which are wound about two of the adjacent longitudinal strands, and each short strand has a single coil and an upwardly-projecting point 3 and a downwardly-projecting point 4.

The strands 2 are arranged in break-joint fashion, those connecting the two top strands being located substantially in line with those connecting the third and fourth, and the fifth and sixth, &c., and those connecting the second and third being substantially in line with those connecting the fourth and fifth, and sixth and seventh, &c.

I claim as my invention—

The design for fencing substantially as herein shown and described.

WM. EDENBORN.

In presence of—
E. S. KNIGHT,
N. FINLEY.
